(57) **CLAIM**

The ornamental design for a display housing for recreational vehicle, as shown and described.

DESCRIPTION

FIG. 1 is a perspective view of a display housing for recreational vehicle in accordance with the present invention;

FIG. 2 is another perspective view thereof;

FIG. 3 is a front view thereof;

FIG. 4 is a first side view thereof;

FIG. 5 is a second opposite view thereof;

FIG. 6 is a top view thereof; and,

FIG. 7 is a bottom view thereof.

The even dash broken lines illustrate environmental structure and form no part of the claimed design. The dash-dash-long-dash broken lines illustrate boundaries of the claim and form no part of the claimed design.
